UNITED STATES PATENT OFFICE.

CHARLES F. HOOFER, OF SPOKANE, WASHINGTON.

OIL-FEEDING DEVICE.

1,038,889.

Specification of Letters Patent. Patented Sept. 17, 1912.

Application filed July 22, 1911. Serial No. 639,910.

To all whom it may concern:

Be it known that I, CHARLES F. HOOFER, a citizen of the United States, and a resident of Spokane, in the county of Spokane and State of Washington, have made certain new and useful Improvements in Oil-Feeding Devices, of which the following is a specification.

My invention relates to improvements in oil feeding devices and it consists in the constructions, combinations and arrangements herein described and claimed.

An object of my invention is to provide a device in which the feeding of the oil is accomplished by pneumatic means.

A further object of my invention is to provide an oil feeding device by means of which the flow of oil may be regulated to any degree, within limits.

Other objects and advantages will appear in the following specification and the novel features of the device will be particularly pointed out in the appended claims.

My invention is illustrated in the accompanying drawings forming part of this application in which—

Figure 1 is a central section through the oil feeding device with the coöperating air pump shown diagrammatically, Fig. 2 is a section along the line 2—2 of Fig. 1, Fig. 3 is a plan view of the oil feeding device, Fig. 4 is a section of the lower part of the oil cup, Fig. 5 is a side view of a lower portion of the valve casing, and Fig. 6 is a side view of the oil feeding piston.

In carrying out my invention I provide a main oil receptacle 1 having a base 2, provided with a reduced threaded portion 3 and a smaller reduced threaded portion 4. The base portions 2 and 3 are provided with a central bore 5, the reduced portion 4 is provided with a bore 6, while the portion 3 has a communicating passage 7 connecting the bore 5 with the bore 6. The base portion 2 is also provided with the side grooves 8 and 9.

Secured to the base portion 2 in the interior of the receptacle is a guide yoke 10, which is perforated to permit the passage of a stem 11. The latter passes through the top 12 of the oil cup or receptacle, and is provided on its upper end with a head 13. A spring 14 is disposed between the head 13 and the central portion 15 of the cover or top 12. The lower end of the stem 11 is provided with a portion 16. The stem

11 is threaded at 11^a to engage similar threads 15^a in the central portion 15.

Referring now particularly to Fig. 1 it will be seen that the lower threaded portion 3 is arranged to be screwed into the end of a casing 17 which is threaded at its bottom as shown at 17^a to receive a nipple or other support (not shown). The casing 17 is provided with a branch pipe 18. An inner valve casing 19 is provided, the upper end of this casing being screwed to the portion 4, as shown in the figure. Within the casing 19 is a piston 20 which is provided with resilient bearing strips 21. The piston rod 22 extends through the casing 19, through a plug 23, through the opening 7 into the central bore 5 where it terminates in a piston head 24. The pipe 18 communicates with the interior of the casing 19 by means of the passage 18^a. The pipe 18 is designed to be connected with a pneumatic device P which is designed to force air into the casing 19, and then to withdraw it. Obviously this might be done by any of a number of pneumatic devices but I have illustrated this device diagrammatically, in the simplest form, although in actual practice I shall use a device which forms the subject of another patent application. In the present instance I have shown the pneumatic device P as being provided with a piston p, the reciprocation of which would cause the air to enter and to be withdrawn from the chamber 19.

From the foregoing description of the various parts of the device the operation thereof may be readily understood.

We will assume that the receptacle 1 is filled with oil. This oil runs down through the passages 8 and 9 into the central bore 5, but is prevented from getting farther by reason of the head 24 which fits snugly in the lower part of the bore 5. As the air is forced into the chamber 19 it will cause the piston 20 to rise against the tension of the spring 20^a. As soon as the rod 24 passes the lower end of the grooves 8 and 9 the oil will flow around the head and below it. The movement of the piston 20 may be regulated by turning the rod 11 so that the head 16 will engage the head 24 at different points in the travel of the latter. Now when the air is withdrawn from the chamber 19 the head 24 will descend owing to the pressure of the spring 20^a. As the head descends it will force oil through the space left

between the cut-away portion 22^x of the rod 22 and the walls of the opening 7 (see Figs. 6 and 4). The oil flows into the bore 6 and thence through the openings 6^a into the passages 25 between the chamber 19 and the casing 17, for it will be observed that it cannot get into the interior of the casing 19, owing to the provision of the gasket 26 which is held by the gasket plug 23. The oil flows down through the threaded opening 17^a and may be delivered to any part which needs oiling such as the flanges or locomotive wheels, etc.

The top 12 is pivotally mounted on the plates 12^x and is provided with the lugs 12^y to enable the top to be turned so as to permit the filling of the oil cup or receptacle 1.

I claim:

1. In an oil feeding device, a receptacle provided with a cylindrical extension and having grooves running parallel with and communicating with said extension, a plunger disposed in said extension, a plunger rod having a cut-away portion, a piston head secured to said plunger rod, a chamber for said piston, means for forcing air into and exhausting air from said chamber, an exterior casing surrounding said chamber and spaced therefrom to form a passage way, said passage way being adapted to be connected with the interior of said extension through the movement of said plunger rod.
2. In an oil feeding device, a receptacle provided with a hollow cylindrical extension and having grooves establishing communication between the interior of the receptacle and the interior of said hollow cylindrical

extension, a valve seat within said hollow cylindrical extension, a screw plug for closing the bottom of said cylindrical extension, a plunger valve within said hollow extension arranged to engage said valve seat, a plunger rod having a cut away portion connected at one end of said plunger valve, a piston connected to said plunger rod at the other end, a chamber for said piston, and a spring within said chamber arranged to bear at one end upon said plunger and at the other upon said plug.

3. In an oil feeding device, a receptacle provided with a hollow cylindrical extension and having grooves establishing communication between the interior of the receptacle and the interior of said hollow cylindrical extension, a valve seat within said hollow cylindrical extension, a screw plug for closing the bottom of said cylindrical extension, a plunger valve within said hollow extension arranged to engage said valve seat, a plunger rod having a cut away portion connected at one end of said plunger valve, a piston connected to said plunger rod at the other end, a chamber for said piston, and a spring within said chamber arranged to bear at one end upon said plunger and at the other upon said plug.

CHARLES F. HOOFER.
